CLAIM

The ornamental design for finger probe device, as shown and described.

DESCRIPTION

FIG. 1 is a front perspective view of a finger probe device showing our design.

FIG. 2 is a back perspective view thereof.

FIG. 3 is a front plan view thereof.

FIG. 4 is a back plan view thereof.

FIG. 5 is a left view thereof.

FIG. 6 is a right view thereof.

FIG. 7 is a top view thereof; and,

FIG. 8 is a bottom view thereof.

The broken lines form no part of the claimed design.
